FLUID HEATERS

Johann Kolling, Oberhausen, Germany, assignor to The Babcock & Wilcox Company, New York, N. Y., a corporation of New Jersey

Application January 30, 1953, Serial No. 334,221

4 Claims. (Cl. 122—333)

The present invention relates in general to an improved construction of a fluid heater having a vertically elongated furnace chamber with fuel burning means in the lower part thereof, and a laterally extending convection heating pass at its upper end; and, more particularly, to an improved form of gas flow baffle means in the furnace chamber subjacent to the convection heating pass in a fluid heater of the character described which are arranged to more uniformly distribute the heating gases flowing from the furnace across the fluid heating surfaces positioned in the heating pass, and cooperating with a special arrangement of tubes in a tube bank arranged across the entrance to said heating pass.

In fluid heaters of the character described, there is a tendency for most of the highest temperature heating gases to travel upwardly along the middle portion of the furnace. These gases flow upwardly at a greater velocity than the cooler gases at the sides of the combustion chamber which are retarded by the resistance offered by the furnace walls. This tendency for concentration of hot gases in the middle portion of the furnace results in uneven heating and possible slagging of the fluid heating tubes in the convection heating pass when a slag-forming fuel is burned. This is particularly evident with a furnace chamber having more than four lateral vertical walls which are symmetrically arranged to form a furnace of varying width and depth relative to its transverse center lines and from which the combustion gases flow laterally out of a gas exit opening whose width is equal to the maximum width of the furnace chamber. In such a case not only the hottest but also the greatest quantity of the combustion gases are pressed toward the middle. This unequal temperature distribution of the gases tends to remain until the gases flow past the last fluid heating surface in the convection heating pass. This uneven gas flow is particularly undesirable where vapor superheating tubes are disposed in the convection heating pass, because localized gas hot spots tend to result in tube failure.

The main object of my invention is the provision of an improved construction and arrangement of the furnace chamber in a fluid heater of the character described for controlling the distribution of the heating gases across the width of the convection heating pass by reducing the amount of high temperature gases flowing through the middle portion of the furnace chamber.

A more specific object is the provision of a furnace nose arch or baffle subjacent to the lateral convection heating pass and having a middle portion which projects inwardly to a greater extent than its side portions, thereby correspondingly reducing the gas flow area in the middle portion of the furnace and forcing hotter gases towards the sides of the furnace chamber.

A still further object is the provision of a special construction and arrangement of the tubes in one or more convection heated tube banks which cooperate with the special nose baffle formation in varying the heating gas

2

distribution across the width of the convection heating pass.

For a better understanding of the invention, its operating advantages and specific objects attained by its use, reference should be had to the accompanying drawings and descriptive matter in which I have illustrated and described a preferred embodiment of my invention.

Of the drawings:

Fig. 1 is a sectional elevation taken on the line 1—1 of Fig. 2 of a steam generating unit constructed in accordance with my invention; and

Fig. 2 is a horizontal cross-section taken on the line 2—2 of Fig. 1.

While in its broader aspects my invention is adapted for use in fluid heaters of the general character described, it is particularly designed for use in fluid heaters having a furnace chamber with more than four vertical side walls. In the steam generating unit illustrated, for example, the vertically elongated furnace chamber 1 is an equi-lateral octagon in horizontal cross-section. In each of the walls 3, 4, 5, 6, 7, 8, 9 and 10 is arranged a fluid fuel burner 2, whose axes of discharge are symmetrically arranged tangent to an imaginary circle about the furnace chamber axis. These burners are similarly offset in the corresponding side walls so that they discharge in the same angular direction relative to the circle. The furnace walls are lined with steam generating tubes throughout their height. The rear walls 7, 8 and 9 and corresponding wall tubes are inclined forwardly and then rearwardly at their upper ends to form a wedge-shaped wall or arch structure 11, which defines a throat 24 adjacent the upper end of the furnace chamber and the inclined bottom 25 of a convection heating pass 26 extending laterally from the furnace chamber gas outlet 12. The tubes lining the walls 7, 8 and 9 are connected at their upper ends to an intermediate header 14 extending across the bottom of the gas pass 26. The tubes 15 lining the walls 7 and 9 have vertical upper end portions 16 forming corresponding vertical rear wall sections of the throat 24. A vertical screen bank of steam generating tubes 13 extends upwardly from the header 14 to an external transverse steam and water drum 21. A pendant type bank of multiple looped steam super-heater tubes 22 extends uniformly across the gas pass 26 rearwardly of the screen bank 13. The front walls 3, 4 and 5 extend upwardly above the level of the throat 24 and then at a rearward inclination to form a furnace roof 27 substantially parallel to the inclined bottom 25 and extending across the upper end portion of the tubes 13 to join the roof 28 of the convection gas pass along the rear side of the drum 21.

With the described construction and arrangement, the combustion gases generated in the lower portion of the furnace chamber flow upwardly in the combustion chamber with the greatest quantity, and the hottest, gases concentrating in the middle of the furnace. The resistance caused by the walls retard the flow of gases along the sides of the chamber with the resulting tendency for the gases to take the path of least resistance and flow upwardly through the central portion of the furnace. This uneven combustion gas flow and gas temperature distribution tends to continue during the gas flow laterally through the convection heating pass 26 and would result in undesirable heat transfer conditions throughout the convection heating pass. However, in accordance with my invention, a projecting nose arch or baffle 17 is provided at the throat section 24, and this together with an arrangement of tubes in the tube bank 13 provides a greater resistance to combustion gas flow in the central portion of the furnace and convection heating gas pass, which causes some of the combustion gases in the cen-

tral portion of the furnace and convection heating gas pass to flow towards the sides thereof.

The nose arch 17 is formed by a forward projection of the tubes along the rear wall 8 beyond the plane of the tube portions 16 which forms in horizontal cross-section a symmetrical trapezoid, the sides of which are substantially parallel to the front walls 3, 4 and 5. This projecting structure, or nose arch 17, may be constructed of special tubes in such a way as to allow the gases to pass between the tubes, or as shown, by covering or lining the tubes with refractory material, be made in the form of a solid gas directing baffle.

The bank of steam generating tubes 13 is composed of the four tube row groups 18 and 19 adjacent the sides of the convection heating pass and adjacent tubes bent forwardly to various degrees to form a seven tube row group 20 in the central portion of the pass. This arrangement aids in directing the gas flow towards the opposite sides of the heating pass due to the higher resistance to gas flow offered by the seven tube row arrangement in the central portion compared to the four tube row construction at the sides.

The tube clearance between the superheater tubes transversely to the gas flow direction could also be made closer in the central area of high combustion gas temperatures. This would increase the gas flow resistance in that area and deflect some of the hotter gases towards the sides of the heating pass.

Deflecting combustion gases away from the central portion of the furnace causes an increase in gas flow along the sides of the furnace chamber outlet and a mixing of the hotter and cooler gases in those areas so that the resultant gas flow through the convection heating pass is more homogeneous. When used in conjunction with the described arrangement of convection heated generating tubes and/or superheating tubes for providing a greater gas flow resistance in the central portion of the convection heating pass, the heat transfer throughout the heating pass will be more efficient and the danger of tube failures due to localized hot combustion gases will be minimized.

While in accordance with the provisions of the statutes I have illustrated and described herein the best form of the invention known to me, those skilled in the art will understand that changes may be made in the form of the apparatus without departing from the spirit of the invention covered by my claims, and that certain features of my invention may sometimes be used to advantage without a corresponding use of other features.

What is claimed is:

1. A fluid heating unit comprising walls defining a vertically elongated furnace chamber and a laterally extending convection heating pass opening through the rear of said furnace chamber, said walls including opposed substantially vertical front and rear furnace chamber walls, a bank of vertically extending fluid heating tubes positioned in said convection heating pass and extending across the width thereof, means for burning fuel in the lower portion of said furnace chamber and producing a heating gas flow upwardly therein and thence laterally through said convection heating pass, and means for effecting a substantially uniform temperature and transverse distribution of the gases flowing from said furnace chamber into said convection heating pass comprising an arch projecting inwardly from said rear wall and cooperating with said front wall to define a restricted heating gas flow passage opening at its upper end to the furnace chamber space wherein the gas turns into said convection heating pass, said arch having a central nose portion formed by laterally aligned tubes and projecting inwardly to a greater extent than its side portions, said arch being spaced from said front wall a distance sufficient to provide a heating gas flow area in the central portion of said gas flow passage approximating but smaller than the heating gas flow area at the sides thereof, means for burning fuel in the lower portion of said furnace chamber and producing a heating gas flow upwardly therein and thence laterally through said convection heating pass, and means for effecting a substantially uniform temperature and transverse distribution of the gases flowing from said furnace chamber

create a greater resistance to flow in the central portion of said gas passage than at the sides.

5. A fluid heating unit comprising walls defining a vertically elongated furnace chamber and a laterally extending convection heating pass opening through the rear of said furnace chamber, said walls including opposed substantially vertical front and rear furnace chamber walls, a bank of vertically extending fluid heating tubes positioned in said convection heating pass and extending across the width thereof, means for burning fuel in the lower portion of said furnace chamber and producing a heating gas flow upwardly therein and thence laterally through said convection heating pass, and means for effecting a substantially uniform temperature and transverse distribution of the gases flowing from said furnace chamber into said convection heating pass comprising an arch projecting inwardly from said rear wall and co-operating with said front wall to define a restricted heating gas flow passage opening at its upper end to the furnace chamber space wherein the gas turns into said convection heating pass, said arch having a central nose portion of trapezoidal formation in horizontal cross-section projecting inwardly to a greater extent than its side portions, said arch being spaced from said front wall a distance sufficient to provide a heating gas flow area in the central portion of said gas flow passage approximating but smaller than the heating gas flow area at the sides thereof to create a greater resistance to flow in the central portion of said gas passage than at the sides.

30. 3. A fluid heating unit comprising walls defining a vertically elongated furnace chamber and a laterally extending convection heating pass opening through the rear of said furnace chamber, said walls including opposed substantially vertical front and rear furnace chamber walls, a bank of vertically extending fluid heating tubes positioned in said convection heating pass and extending across the width thereof, means for burning fuel in the lower portion of said furnace chamber and producing a heating gas flow upwardly therein and thence laterally through said convection heating pass, and means for effecting a substantially uniform temperature and transverse distribution of the gases flowing from said furnace chamber into said convection heating pass comprising an arch projecting inwardly from said rear wall and co-operating with said front wall to define a restricted heating gas flow passage opening at its upper end to the furnace chamber space wherein the gas turns into said convection heating pass, said arch having a central nose portion of trapezoidal formation in horizontal cross-section projecting inwardly to a greater extent than its side portions, said arch being spaced from said front wall a distance sufficient to provide a heating gas flow area in the central portion of said gas flow passage approximating but smaller than the heating gas flow area at the sides thereof to create a greater resistance to flow in the central portion of said gas passage than at the sides, said front wall including vertical portions parallel to sides of the central nose portion of said arch.

35. 4. A fluid heating unit comprising walls defining a vertically elongated furnace chamber and a laterally extending convection heating pass opening through the rear of said furnace chamber, said walls including opposed substantially vertical front and rear furnace chamber walls, a bank of vertically extending fluid heating tubes positioned in said convection heating pass and extending across the width thereof, some of said tubes extending further toward the furnace chamber in the center part of the convection heating pass than those at the sides thereof, means for burning fuel in the lower portion of said furnace chamber and producing a heating gas flow upwardly therein and thence laterally through said convection heating pass, and means for effecting a substantially uniform temperature and transverse distribution of the gases flowing from said furnace chamber

into said convection heating pass comprising an arch projecting inwardly from said rear wall and cooperating with said front wall to define a restricted heating gas flow passage opening at its upper end to the furnace chamber space wherein the gas turns into said convection heating pass, said arch having a central nose portion formed by laterally aligned tubes and projecting inwardly to a greater extent than its side portions, said arch being spaced from said front wall a distance sufficient to provide a heating gas flow area in the central portion of said gas flow passage approximating but smaller than

the heating gas flow area at the sides thereof to create a greater resistance to flow in the central portion of said gas passage than at the sides.
